SWITCHBOARD PLUG

Harry C. Calvin, Dothan, Ala., assignor of one-fourth to Earle C. Moody, Dothan, Ala.

Application September 3, 1943, Serial No. 501,171

3 Claims. (Cl. 173—361)

1

This invention relates to flexible electrical plugs, and more particularly to a flexible telephone switchboard plug.

The conventional switchboard plug comprises a substantially elongated body having tip, ring and sleeve contacts engageable with coacting contacts in the switchboard jack openings, and a flexible cable extends to the plug and contains three wires connected to the respective contacts referred to. The flexible cable, upon insertion of the plug into the jack, is subjected to the force of the operator's fingers or palm to push the plug into position, and this force causes the covering of the cable to cut and break against the base of the plug thereby exposing the conductors therein. This puts the entire strain on the conductors themselves which, sooner or later, weakens the conductors to the breaking point. When the plug is pulled and dropped to its normal position, the cable tends to straighten to a position in alignment with the plug. This constant bending and straightening of the cable aggravates the condition referred to and accelerates crystallization and breaking of the wires in the cable, thus requiring the repairing of the electrical connections.

An important object of the present invention is to provide a novel flexible electrical plug, and more particularly a telephone switchboard plug, wherein the bending of the cable relative to the plug is limited and wherein the cable is relieved of the pressure usually exerted thereagainst by the operator.

A further object is to provide such an arrangement wherein the cable extends through a thimble pivoted to the body of the plug and engageable therewith to limit the turning movement of the thimble relative to the plug, and thus limit the bending of the cable.

A further object is to provide a telephone switchboard plug of the type referred to wherein the pivoted thimble is utilized for the grounding of the wire usually connected to the sleeve contact of the plug, thus completely eliminating the bending of one of the three wires employed in connection with a plug of this character.

A further object is to provide such a device wherein a pivoted thimble is ribbed or threaded internally for engagement with the cable to fix the latter firmly with respect to the cable, thus effectively securing the parts together and at the same time preventing the pulling of the cable from exerting a pull on the wires and their connections with the associated contact elements.

Other objects and advantages of the invention

2

will become apparent during the course of the following description.

In the drawing I have shown one embodiment of the invention. In this showing:

5 Figure 1 is a perspective view of the device shown in conjunction with a portion of a telephone switch board.

Figure 2 is a side elevation of the device showing the thimble in the turned position it assumes 10 when the plug is inserted in the jack, parts being broken away and parts being shown in section, and

15 Figure 3 is an enlarged sectional view of the sleeve and a portion of the plug, parts being shown in elevation.

Referring to the drawing, the numeral 10 designates a conventional telephone switchboard having jack openings 11 in which is insertable a plug indicated as a whole by the numeral 12. 20 This plug is provided with the usual tip contact 13, ring contact 14 and sleeve contact 15 which are engageable with the three conventional jack contacts to complete the necessary telephone circuits. The projecting portion of the plug carrying the three contacts referred to is carried by a fiber or similar body 16. Three wires, to be referred to later, extend through this body for connection with the respective contacts 13, 14 and 15.

30 The elements described may be conventional in every way, and in the usual switchboard plug, the three wires, arranged in a cable, extend directly from the body 16 and downwardly at an angle, when the plug is inserted. It is the downward bending of the wires which results in their breaking, and it is this disadvantageous result which is overcome by the present construction. The body 16 is provided with a preferably metallic ferrule 17 having its end remote from the body

portions of the ferrule 17, as indicated in Figure 2.

The cable for the wires is indicated by the numeral 23, and this cable contains three wires 24, 25 and 26, and the wires 24 and 25 extend through the body 16 and through the sleeve 15 for connection with the respective contacts 13 and 14. In conventional constructions the third wire 26 extends through the body 16 for connection with the contact 15. In the present instance, however, the cable 23 terminates short of the inner end of the thimble 22 and a short end of the wire 26 is stripped as at 27 and soldered to the thimble 22 to be thus grounded thereon. This thimble will be electrically connected, of course, to the ferrule 17 through the arms 21. The ferrule 17 is integral with or permanently connected to a sleeve 17', forming a part of the sleeve contact 15. Accordingly, the soldering of the wire end 27 establishes electrical connection between such element and the sleeve contact 15.

In order to rigidly secure the cable 23 to the thimble 22 so that any pull on the cable will be transmitted directly to the thimble and not to the wires 24, 25 or 26 the interior of the thimble 22 is ridged as at 28 (Figure 3). These ridges are preferably in the form of threads which will embed themselves in the cable covering and thus afford an effective mechanical connection between the cable 23 and thimble 22.

The operation of the device will be apparent from the foregoing description. As previously stated, the cable 23 ordinarily projects directly from the body of the plug 12, and extends downwardly at an angle therefrom when the plug is inserted into the jack, or is arranged horizontally in a position for such operation. In pushing the plug into the jack, the operator usually presses against the cable at the point where the bend occurs therein, and this pressure tends to cut the cable covering and place the entire strain on the conductors. This, together with the bending of the wires at each insertion of the plug, causes the wires to crystallize and break after relatively short use.

In the present device, the thimble 22 limits the bending of the wires and forms a rigid finger piece against which the operator may push in inserting the plug, instead of pushing directly on the cable. Thus the wires are relieved of the destructive force ordinarily exerted thereagainst by the operator.

Moreover, the thimble is advantageous for two other reasons. In the first place it limits the bending of the wires, the parts being designed so that the thimble 22 preferably cannot turn to an angle of greater than 45° with respect to the plug. This limiting of the bending of the wires also lengthens the life of the wires by minimizing crystallization of the metal of the wires which occurs incident to bending. In the second place the thimble 22 permits the third wire 26 to be electrically connected to its associated contact 15 without having to extend from the thimble 22. Therefore, the bending of one of the wires is eliminated completely, and more space is provided for the remaining two wires. The latter fact eliminates crowding of the wire at the points where they bend, and permits the wires to partake of freer movement without sharp bending. The various features of the device, therefore, obviously cooperate to greatly lengthen the life of the wires.

It is to be understood that the form of the invention herewith shown and described is to be

taken as a preferred example of the same and that various changes in the shape, size and arrangement of parts may be resorted to without departing from the spirit of the invention or the scope of the subjoined claims.

I claim:

1. A flexible electrical connection plug comprising a plug body having a plurality of contacts at one end portion thereof, a cylindrical ferrule carried by said body at the opposite end thereof, said ferrule having diametrically opposite portions projecting longitudinally therefrom as continuations thereof, a cylindrical thimble substantially equal in diameter to and normally arranged in axial alignment with said ferrule and provided with diametrically opposite portions projecting longitudinally therefrom and each lying radially outwardly of and contacting with one of the projecting portions of said ferrule, the adjacent ends of said thimble and said ferrule being open and unobstructed for the passage of wires therethrough, and a pivot pin projecting through each projecting portion of said thimble and the corresponding projecting portion of said ferrule to pivotally connect said thimble and said ferrule to each other, the wires engaging against the inner surface of said ferrule to be bent thereby when said thimble swings about the pivot axis of said pins relative to said ferrule, the contacting surfaces of the projecting portions of said ferrule and said thimble forming the sole frictional contact between said thimble and said ferrule during turning movement thereof relative to each other.

2. A telephone switchboard plug comprising a plug body having a plurality of contacts at one end portion thereof and an open ended cylindrical ferrule at the other end thereof, said ferrule having diametrically opposite portions projecting longitudinally therefrom as continuations thereof, an open ended cylindrical thimble substantially equal in diameter to said ferrule and normally arranged in axial alignment therewith, a pair of parallel arms fixed to said thimble diametrically opposite each other, said arms extending longitudinally of said thimble and overlying the projections of said ferrule radially outwardly thereof and in contact therewith, the adjacent open ends of said ferrule and said thimble being unobstructed for the passage of wires therethrough, and a pivot pin projecting through each arm and the corresponding projection of said thimble, said pins being in axial alignment to pivotally connect said thimble and said ferrule to each other and the contacting surfaces of said arms and the projections of said thimble constituting the sole frictional engagement between said ferrule and said thimble during relative turning movement thereof about said axis, said thimble and said ferrule being adapted for the passage therethrough of wires engageable with the inner surface of said ferrule to be bent thereby when said thimble is turned about said axis relative to said ferrule.

3. A telephone switchboard plug comprising a plug body having a plurality of contacts at one end portion thereof and an open ended cylindrical ferrule at the other end thereof, said ferrule having diametrically opposite portions projecting longitudinally therefrom as continuations thereof, an open ended cylindrical thimble substantially equal in diameter to said ferrule and normally arranged in axial alignment therewith, a pair of parallel arms fixed to said thimble diametrically opposite each other, said arms extending longitudinally of said thimble and overlying the projections of said ferrule radially outwardly there-

of and in contact therewith, the adjacent open ends of said ferrule and said thimble being unobstructed for the passage of wires therethrough, and a pivot pin projecting through each arm and the corresponding projection of said thimble, said pins being in axial alignment to pivotally connect said thimble and said ferrule to each other and the contacting surfaces of said arms and the projections of said thimble constituting the sole frictional engagement between said ferrule and said thimble during relative turning movement thereof about said axis, said thimble and said ferrule being adapted for the passage therethrough of wires engageable with the inner surface of said ferrule to be bent thereby when said thimble is turned about said axis relative to said ferrule, the ends of said thimble between the projections thereof being engageable with the adjacent ends

of said ferrule to predetermine and limit relative swinging movement of said ferrule and said thimble about said pivot axis.

HARRY C. CALVIN.
